UNITED STATES PATENT OFFICE.

JOHN W. STREHLI, OF CINCINNATI, OHIO.

BARREL.

No. 923,461.

Specification of Letters Patent.

Patented June 1, 1909.

Application filed February 12, 1908. Serial No. 415,502.

To all whom it may concern:

Be it known that I, JOHN W. STREHLI, a citizen of the United States, residing at the city of Cincinnati, in the county of Hamilton and State of Ohio, have invented certain new and useful Improvements in Barrels, of which the following is a specification.

My improvement relates particularly to barrels for holding liquids, known in the art 10 as "tight packages".

In my package the staves are of an uniform thickness throughout, except at their ends where they are cut away on the inside; the heads are thin, and a metal cap fits over 15 the barrel ends, and a plastic, viscous, adhesive, glutinous or sticky mass is placed between the top of the wooden head and the metal cap.

The metal cap is provided with a series 20 of slots, through some of which are passed screws, shouldered nails or the like, which enter the staves; by these means the cap is held in place over the barrel end. At certain points the cap is provided with inwardly 25 bent tongues, burs or tangs which enter the stave when the cap is pulled in place; these also aid in holding the cap on the barrel. By combining these elements together, I form a novel and unique barrel or pack- 30 age; its advantages and features will readily become apparent from the following specification.

In the accompanying drawing forming 35 part of this specification. Figure 1 is an isometric view of my new improved barrel. Fig. 2 is a section through the stave, head, metal cap, plastic matter, the section being taken at a point where the slots and retaining screw are present, the parts being broken 40 away. Fig. 3 is a similar section except that it is taken at the point where one of the tangs is present on the cap, and, Fig. 4 is a similar section except that the section is taken where a shouldered nail is employed 45 to hold the cap on the barrel. In Fig. 2, the head is shown entering a short croze and in Figs. 3 and 4 the head and edge of the stave on the inside are shown on an incline.

The body of the barrel is formed of oak 50 staves, 1, tightly joined together and bound by heavy iron hoops 2. These staves are of an uniform thickness throughout and at their ends are rounded and on the inside

are cut away or inclined. I use a thin wooden head 3, either fitting a croze 4, or 55 an incline 5. In the first instance the head 3 has a V shaped edge 6, and in the latter instance an inclined or tapered edge 7.

Over the ends of the staves and head which are held together by hoops 2, I tightly 60 clamp or force a metal cap formed of a head 8, provided with a tap hole 9, a raised or chime part, ridge or rim 10, which extends and bends over the top edge of the staves 1, and an annular depending flange 65 11; the rim or chime part 10, impinges against the inside of the stave end on the incline 5, and the depending flange encircles the periphery of the barrel at the top, im- 70 pinging against all the staves.

In the depending flange 11 of the cap, at 75 intervals, I form tangs 12 by upsetting the metal. These tangs 12 are forced into the staves when the cap is pressed onto the barrel ends, (see Fig. 3).

The depending flange 11 of the cap is also provided with a series of elongated slots 13. Through these slots 13, at their lower edge, I use screws 14 or shouldered or barbed nails 15. The head on the screws 14 or barbed 80 nails 15, rest against the lower edge of the slot keeping the cap from moving upward and holding it in place in connection with the tangs 12. I place the screws or tangs in several of the slots only, inasmuch as a few 85 are sufficient to do the work; a multiplicity of slots being however provided, so that, if the cap from any cause, as for instance shrinkage or displacement needs to be tightened, the cap can be pressed further down 90 on the staves and several new screws or barbed nails placed in any of the other slots, the old ones remaining; the new ones which have been used for holding the cap in its new position on the barrel end and the old 95 ones not interfering in any manner, although the end of the slot has passed away from them, they still act as auxiliary aids in holding the cap in place. This re-tightening and adjustment of the cap can be done as 100 often as is required during the life of the keg on account of the multiplicity of slots used together with the screws or nails.

Between the top of the wooden head 3 and the part 8 of the metal cap, I place the 105 plastic, viscous and sticky mass 16. I pref-

erably leave a space 17 between the top edge of the staves 1 and the top edge of the cap where the rim 10 and the depending flange 11 unite and meet over the stave ends.

5 I also preferably place a plastic or viscous mass 18 in this space 17 (see Figs. 2 and 3). In Fig. 4 I have however left out this plastic mass. This space is left so that the cap can be tightened or repulled if necessary, and

10 also so that the plastic filler can be used to assist in making a tight joint. This plastic or viscous mass may be made out of any preferred substance, as for instance, rosin and paraffin, shellac in liquid form, soft

15 pitch or asphaltum, soft gum or such like substances preferably used in such a state that they will not readily become hard or congeal or coagulate to any degree and remain in a plastic or semi-plastic condition,

20 so that the heat applied to the inside of the keg when it is pitched, which heat is 400 degrees to 450 degrees Fahrenheit, will effect said mass that it will fill any pore, opening, interstice, crack or the like present

25 around the head or stave joints around the head and form an air tight filler at the head and at the stave ends also. In this manner every time the hoops are repulled on account of shrinkage or re-pitching of the keg,

30 the plastic mass will act as if automatic to fill any defect and insure a tight head for the package. When the cap is forced onto the barrel this mass will also fill all defects and accommodate itself to all irregularities

35 in the stave ends and head and the wood around the head, making an absolutely tight joint. In this manner it will be seen that I seal the package on the outside at the heads as well as on the inside of the heads.

40 Shrinkage is cut down to a minimum as the pores are not exposed to the elements. In winter when the shrinkage is least the plastic filler will not be affected to any extent and in the summer when the shrinkage

45 is greatest, if any slight leak would become apparent in a barrel as now made, in my package, the filler would prevent such a result, as it would fill in any defect on account of the effect of the summer heat on the plastic mass.

50 My barrel can be made cheaper, is lighter and more uniform than the barrel now used. The shrinkage being very slight the barrel capacity is kept uniform, as the hoops or

55 caps need not be re-pulled, but a few times during the life of the keg; but in the barrel now used the shrinkage being great, the hoops must often be repulled, thus decreasing the capacity of the barrel.

60 By forming an inclined edge on the stave ends and edge of heads, when the hoops or caps are pressed down the head and staves will accommodate themselves to the pres-

sure exerted and the downward movements of the caps will not be limited by the heads 6 inasmuch as they are not in a croze.

The cap may be made of any shape and held in place as desired and if desired the stave ends may be made blunt.

What I claim as new and of my invention 7 and desire to secure by Letters Patent is:

1. A barrel composed of staves tightly joined and bound together, heads, said heads fitting into the barrel ends, caps, said caps fitting over the barrel ends and being adjustable toward said heads, a plastic filler, said filler interposed between the barrel head and cap as set forth.

2. A barrel composed of staves tightly joined and bound together, heads, said heads fitting into the barrel ends, caps, said caps fitting over the barrel ends and being adjustable toward said heads, a plastic filler, said plastic filler interposed between the head and the cap and between the ends of the staves and top of cap at chime, as set forth.

3. A barrel composed of staves tightly joined and bound together, the staves inclined at their inner top edges, heads, said heads having inclined edges, the inclined edges on the heads fitting and resting on the inclined edges of the staves, caps, said caps fitting over the barrel ends and being adjustable toward said heads, means for holding said caps on the barrel, combined and operating as set forth.

4. A barrel composed of staves, tightly joined and bound together, the staves, inclined at their inner upper edges, heads, said heads having inclined edges, the inclined edges on the heads fitting the inclined edge on the staves, caps, said caps fitting over the barrel ends and being adjustable toward said heads, means for holding said caps on the barrel, a plastic filler, said filler interposed between the head and the caps, as and for the purposes set forth.

5. A barrel composed of staves tightly joined and bound together, inclined edges at the ends of said staves, heads, inclined edges on said heads, the inclined edges on the heads fitting onto the inclined edges of the stave ends, in combination with a metal cap, said cap fitting over the barrel ends and being adjustable toward said heads, and means for holding said cap on the barrel ends, as set forth.

6. A barrel composed of staves having projecting tapering edge portions, heads within the ends of the barrel, metal caps inclosing the barrel ends and each having a central depressed portion and chime portion, the chime portion having inclined walls inclosing and wedging upon the tapering edge portions of the staves, and

packing intermediate the chime portion of the caps and the stave ends and packing intermediate the depressed portions of the caps and the said heads.

5 7. A barrel composed of staves tightly joined and bound together, heads, said heads fitting into the barrel ends, caps, said caps fitting over the barrel ends, a plastic filler,

16
said filler interposed between the barrel head and cap, as set forth.

Signed at Cincinnati, Ohio, February 7th
